COMBINED CYLINDER VALVE AND GAUGE FOR COMPRESSED GAS CYLINDERS

Franz Wagner, Chicago, Ill., assignor to Ansul
Chemical Company, Marinette, Wis., a corpora-
tion of Wisconsin

Application December 1, 1953, Serial No. 27,858

Term of patent 14 years

(Cl. D78—1)

To all whom it may concern:

Be it known that I, Franz Wagner, a citizen
of the United States, residing at 444 North Michigan
Avenue, Chicago, Illinois, have invented a
new, original, and ornamental Design for a Com-
bined Cylinder Valve and Gage for Compressed Gas
Cylinders, of which the following is a
specification, reference being had to the accom-
panying drawing forming a part thereof, in
which:

Figure 1 is a front view of the combined cylin-
der valve and gage for compressed gas cylinders
showing my new design,

Figure 2 is a right-hand side view thereof,

Figure 3 is a plan view thereof,
Figure 4 is a rear view thereof, and
Figure 5 is a left-hand side view thereof.

I claim:

The ornamental design for a combined cylin-
der valve and gage for compressed gas cylinders,
as shown.
